UNITED STATES PATENT OFFICE.

RALPH R. SHAY, OF CHICAGO, ILLINOIS, ASSIGNOR TO PAPER UTILITIES CORPORATION, OF CHICAGO, ILLINOIS, A CORPORATION OF ILLINOIS.

MACHINE FOR FEEDING STRIPS AND THE LIKE.

Application filed August 24, 1927. Serial No. 215,122.

This invention has to do with certain improvements in machines for feeding such objects as strips of paper, labels, gummed cloth, stamps, etc. More particularly, the invention has reference to improvements in machines for feeding strips of gummed paper such as are used for sealing packages and for similar purposes. These machines are ordinarily placed on counters or tables where they are convenient of access for operation. The usefulness of the invention is not limited to the same, however.

One of the objects of the invention is to provide the machine with one or more feet or pedestals of such a nature as to take hold of the surface upon which the machine is placed and firmly attach themselves thereto so as to hold the machine securely in the selected location. At the same time, these feet are of such construction that they will not in any manner injure or mar the surface of the table or counter.

More particularly, it is an object of the invention in this connection to make use of a series of vacuum cups for holding the machine in place, said cups being a definite part of the machine and serving not only as the feet or legs thereof, but also serving the useful purpose already referred to.

Another feature of the invention relates to the provision of a greatly improved arrangement of moistening device for moistening the gummed surface as the object is delivered from the machine. This moistening device is constructed and arranged in the form of a self-contained unit which can be readily set into place or removed from the front portion of the machine proper, and when so set in place it is so arranged that the moisture will be delivered against the bottom surface of the object in the proper quantities and in the exact position desired. This moistening device constitutes the subject matter of another companion application for Letters Patent of the United States, Serial No. 265,706, filed March 29, 1928; but it bears a peculiar relationship to the other mechanisms which are disclosed in the present application.

Another feature of the invention relates to the provision of an improved form of feeding device for feeding forward the tape or other object. This feeding device is so arranged as to very effectively grip the strip or tape or other object, but is of an extremely simple design.

A further feature of the invention relates to the provision of an improved construction of guide for the paper strip or other object. This guide is so arranged that as the tape enters the guide it is centered with respect to the guide even though the tape itself may not be of full width. By this means there is assurance that the tape will be properly centered and advanced without complications or tendency to jam in the machine notwithstanding the fact that the tape is of less than the normal intended width.

By reason of the foregoing feature it is possible to use tapes of varying widths less than the full capacity of the machine, so that it is possible to use a standard size and construction of machine for filling the needs of many different classes of users.

A further feature of the invention relates to the provision of a paper strip or tape guide in the form of a self-contained unit which can be very easily set into place in the machine proper or removed therefrom either for replacement or repair. This self-contained unit also includes the tape feeding jaws which travel upon the guide. The arrangement is such that when this unit, including the tape feeding jaws, is set into place in the machine, the necessary operative connection is established between the operating lever and similar parts and the tape feeding jaws, and without the necessity of special mechanical adjustments or connections, and also without the need of using special tools. By reason of this arrangement it is possible for a user of the machine to remove the tape guide and feeding jaw unit and return the same to the factory for adjustments, and it is also possible for the user to readily replace the adjusted parts or to substitute a new unit.

Another feature of the invention relates to the provision of an improved form of knife and cutting mechanism for severing the tape automatically after it has been fed. This construction is such that the feed of the tape takes place on the forward stroke of the operating handle, the cutting blade being dropped out of the way at that time; and it is also such that on the return stroke the cutting blade is forcibly operated to sever the tape.

Another feature of the invention relates to the provision of a very simple form and arrangement of operating mechanism for oper-

ating the tape feeding jaws and the cutting blade in proper sequence and in proper timing. This operating mechanism is composed of a minimum number of parts which can be 5 readily assembled.

Other objects and uses of the invention will appear from a detailed description of the same, which consists in the features of construction and combinations of parts herein-10 after described and claimed.

In the drawings,—

Fig. 1 shows a vertical longitudinal section through a machine embodying the features of the present invention, being taken substantially on the line 1—1 of Fig. 2, looking in the direction of the arrows;

Fig. 2 shows a plan view corresponding to Fig. 1;

Fig. 3 shows a broken horizontal section 20 substantially on the line 3—3 of Fig. 1, looking in the direction of the arrows;

Fig. 4 shows a vertical cross section on the line 4—4 of Fig. 1, looking in the direction of the arrows, and illustrating particularly 25 the knife and operating mechanisms;

Fig. 5 shows a cross section on the line 5—5 of Fig. 1, looking in the direction of the arrows;

Fig. 6 shows a fragmentary, horizontal section 30 on the line 6—6 of Fig. 5 looking in the direction of the arrows, but on an enlarged scale; and

Fig. 7 is a detail face view of the tape guide unit removed from the frame of the machine.

The machine herein disclosed includes a base member 7, which may be in the form of a casting or may be made of pressed metal. It is preferably provided with the downwardly 35 extending, encircling flange 8. This flange serves to reinforce the base and at the same time to give it a more finished appearance.

In its central rear portion the base 7 is provided with a cup-shaped recess 9, the front portion 10 of which is preferably of some-40 what higher elevation than the rear portion 11, since the tendency is for the roll of tape to ride up over the front portion 10 when the tape is being fed.

In conjunction with this base member there 45 is a pair of side walls 12 and 13. Either or both of these may be made as separate units independently attached to the base member 7, or one of said side plates may be formed integrally with the base member. In the particular construction illustrated, the side plates 50 12 and 13 are made of sheet metal having their lower edges flanged inwardly, as shown at 14, so as to rest directly upon the top surface of the base member to which they are 55 then connected by means of screws 15, or in any other convenient manner.

The upper portions of the side plates are 60 also flanged inwardly, as shown at 16 in Fig. 5 in particular, so as to give the top portion of the machine a finished appearance and

also to provide suitable means to which the guide unit may be connected.

The upper portions of the side walls 12 and 13 are curved on a substantially circular arc, as shown at 17 in Fig. 1, which arc extends 70 from the point 18 substantially to the point 19. At the point 19 the top edges of the side walls are curved and carried straight forward for a relatively short distance, at which position the tape is moistened and delivered. 75

The rear portion of the housing may be closed by means of a vertical slide plate 20, the upper end of which has a forwardly projecting finger 21 which serves both as a convenient means for raising the slide plate when 80 a new roll of tape is to be inserted, and also serves to more or less enclose the extreme rear portion of the top opening between the side plates. The vertical slide member 20 sets 85 down immediately in front of the flanges 22 on the rear ends of the side plates 12 and 13; and lugs 23 on the base member 7 are so positioned as to hold the lower end of the slide 20 against being moved forwardly when the slide is set into place. 90

The guide unit 24 is set into place adjacent to the upper edges of the side plates and serves to more or less completely enclose the upper portion of the opening between them. This unit is made of sheet metal, and comprises upper and lower or front and rear cross pieces 25 and 26, together with the intervening, connecting, curved, folded sections 27 and 28. These sections 27 and 28 are folded back upon themselves, as clearly shown in 95 Fig. 5 in particular, to thereby establish the longitudinal guide slots which face each other and accommodate the edge portions of the tape which is being fed.

Intermediate between the guide portions 27 and 28 there is the longitudinal slot 29, the ends of which are defined by the cross pieces 25 and 26 already referred to.

The upper and lower cross pieces 25 and 26 are provided with the side ears 30, which rest 105 upon the upper flanged edges of the side plates 12 and 13, to which they may be connected in any convenient manner, as by screws 31. The ears at the front or lower end of the guide member 24 do not appear in Fig. 2, for 110 the reason that they are covered over and hidden by the bracket presently to be explained.

There is a tape gripping and feeding carriage 32 which is slidably mounted upon the guide 24. This carriage includes a plate 33 115 which extends over and rests upon the sections 27 and 28; and the ends of the plate 33 are folded back under, as shown at 34 and 35 in Fig. 5, so as to more or less completely 120 embrace the members 27 and 28 of the guide 125 section. The extreme inner ends of the re-entrant portions 34 and 35 are provided with downwardly depending ears 36, as shown in Fig. 5; and a cross pin 37 is extended through 130 said ears and serves as a pivot or support for

- the jaw member 38 (best shown in Fig. 1). This jaw member is preferably made of sheet metal and is bifurcated, having a pair of companion forwardly reaching arms 39 and 40, and a corresponding pair of downwardly depending ears 41 and 42. Between the forwardly reaching arms 39 and 40 there is placed a small rubber block 43 which has the ear 44 which extends upwardly above the 5 positions of the arms, so that said ear 44 can directly contact the lower surface of the tape and bite against the same. The two downwardly depending arms 41 and 42 are protected by a sleeve of rubber or the like 45.
- 10 The member 33 is provided with a semi-perforation or a depression 46, which is adapted to travel in the slot 29 of the guide section, and reaches down into position to serve as an abutment against which the top surface of the 15 tape will be pressed by the rubber ear 44.
- The arrangement is such that upon forcing the jaw member 38 forward by pressing against the downwardly depending arm thereof, the ear 44 will be raised against the 20 bottom surface of the tape, and the tape will thus be clamped between said ear 44 and the semi-perforation 46. The forward movement of the member 38 will thus effectively feed the tape; and the bite of the parts against the 25 tape will be increased in direct proportion to the resistance which the tape offers against being advanced.
- Within the casing there is pivotally mounted an operating arm 47. This arm is provided 30 at its upper end with a forward extension 48. The lower end of the arm is pivoted at the point 49 to a lug 50 which extends upward from the base member 7 at one side of the pocket 9 which receives the roll of tape.
- 35 A slot 51 is formed in the side wall 12 on a circular arc drawn about the pivotal point 49. A handle pin 52 is placed on the front end of the extension 48 and reaches through said slot, and is provided with a handle button 53 on its outside end. By this means the arm 47 can be drawn forward with an easy motion communicated by the right hand of the user when facing the machine in the natural manner.
- 40 On its upper end the arm 47 also carries a lug 54, which extends sidewise a sufficient distance to embrace the vertical arm of the jaw member 38. For this purpose, said lug 54 is provided with a central opening 55 (see Fig. 45 in particular) which is preferably of ample size and elongated in a front and rearwardly direction. This elongation allows for a certain amount of lost motion, to be presently explained. At the same time, by making the 50 opening 55 amply large laterally, it is possible to set the guide unit 17 down into place on the structure of the machine and cause the vertical arms of the jaw member 38 to properly seat through the opening 55 without 55 the necessity of special or difficult adjustments by the worker. It is thus possible for the user to either lift the unit 17, together with the jaw member, upwardly away from the operating lever and other parts without the need of disconnecting any other elements, and in like manner it is possible for the user to set said member back into place without difficulty. This member 17, together with the feeding jaws and associated parts may therefore be readily treated and used as a unit. 75
- A spring 56 tends to draw the lever 47 backwardly to the rear limit of movement, and thus also to restore the jaw member already referred to.
- The extreme front end of the guide member 17 is deflected into a horizontal direction at the point 26, as already explained. Thus the advancing tape is delivered in a horizontal path. Immediately above the cross piece 26 already referred to there is placed a bracket 80 member 57, the same extending sidewise far enough to overlie the front portion of the guide member 17. This bracket member 57 carries a stationary blade 58, which is secured to its front face, the lower edge of said blade 85 being sharpened. Another swinging blade 59 is pivoted at the point 60 to one end of the stationary blade and to the bracket 57. This swinging jaw 59 is preferably of somewhat triangular form, as shown in Fig. 4, so as to 90 give it additional weight and thus improve its tendency to fall into the open position. The upper edge of the jaw 59 is sharpened and 95 co-operates with the fixed jaw 58.
- There is a stiff wire rod 61 in the body of the 100 machine, one end 62 of the same being hooked into an opening 63 of the base member 7, which thus acts as a pivot point. The other end of said rod 61 is extended somewhat loosely through an opening 64 in the swinging portion of the jaw 59, so that by raising the arm 61 on the pivot point 62 the jaw 59 is 105 raised and the tape is severed.
- There is a chain 65 which has one end connected to the lever extension 48. The other end of said chain 65 is connected to a loop 66 formed in the wire rod 61. The chain is made of proper length to pick up the lever 61 and raise the same so as to throw the jaw 59 into the cutting position just before the lever 47 110 and connected parts reach the rear limit of their return movement. In this way the tape is severed as the last operation on the return stroke.
- The opening 55 already referred to is of sufficient length to allow the lever 47 to be drawn forward such a distance at the beginning of the next operating stroke as to completely 115 lower the cutting blade 59 before the jaw member 38 is properly engaged to commence the feed of the paper strip. This lost motion, therefore, makes it possible to drop the cutting blade 59 out of the way before the advancement of the tape actually commences, so that there will be no interference with the 120
- 125 130

advance of the tape when the proper time arrives.

On the back or returning stroke of the lever 47, the jaw member 38 is thrown backwardly with a quick jerky movement. This might tend to cause said jaw member to occupy the extreme rearward position with respect to the slot 55, so that the jaw member 38 would be prematurely advanced at the beginning of 10 the next feeding operation. In order to eliminate such possibility, I have provided a light spring 67 which is fastened to a suitable, stationary part and engages the downwardly depending arm of the jaw member so 15 as to hold the jaw member 38 at the front end of the slot 55 when the parts have come to rest. There is another spring 67^a, lighter than the spring 67, and connected to the finger 54. The free end of the spring 67^a tends to 20 push the carriage 18 backwardly until limited by engagement of the finger 36 with the back edge of the slot 55. This will ensure that the lever 47 moves forward the amount of lost motion of the slot 55 before actual forward 25 movement of the carriage 18 begins.

In order to assist in centering the tape or strip and delivering the same centrally along the guide member 17, I have provided a downwardly depending ear 68 at the 30 rear end of said guide member. This ear 68 is shown in detail in Fig. 6, from which it will be seen that it is curved on a smooth curve facing towards the rear of the machine so that as the tape rises it will tend 35 to draw to the center of this curvature. Then as the tape passes up over the top edge of the ear and starts advancing forwardly along the guide member under the impulse of the jaw member 38 it will be properly centered and 40 will feed to best advantage. It has been found that this arrangement will ensure a correct centering and feed of the tape even in those cases in which the tape itself is very 45 much narrower than the full capacity of the machine.

In order to create an additional slight resistance to the movement of the tape up and over the rear end of the guide 17 so as to further improve the biting action of the jaw member 38, I have provided a small spring 69 which is located in the slot 29 of the guide member 17 and immediately in advance of the 50 position at which the tape rides into the guide member. This spring member normally stands at such a raised position, as shown in Fig. 1 that it will press against the central portion of the tape as the latter passes into the guide.

I have herein illustrated a suitable form of 60 guide member 70 for receiving the tape after it passes the position of the cutting blades, and have also herein illustrated a suitable moistening device 71 for moistening the gummed surface of the tape as it is served; 65 but inasmuch as these features constitute the

subject matter of another application for Letters Patent of the United States, I do not herein describe the same in greater detail.

In order to support the base member 7 in a firm and even manner, and in order to prevent marring the surfaces upon which the machine may be placed, I have provided the feet 72, such as shown in the different figures. These are formed of rubber dished out, as shown in Fig. 1, so as to establish in effect 75 downwardly-facing vacuum cups which will take hold of the smooth surface upon which the machine is placed and adhere thereto in a very firm manner. These vacuum cups are readily connected to the base member 17 by 80 screws or rivets 73, as shown in Fig. 1.

While I have herein referred to the feeding of tape, it will be understood that machines embodying the features of my invention may also be used for feeding other objects such as 85 stamps, labels, etc. Therefore, when I speak of "tape" it will be understood that I use this word as illustrative only.

While I have herein shown and described only a single embodiment of the features of 90 my present invention, still I do not intend to limit myself thereto except as I may do so in the claims.

I claim:

1. In a machine of the class described the 95 combination of a base member, a pair of parallel vertical side plates projecting upwardly from the base member, the upper portions of said side plates curving downwardly from the upper rear corners towards the 100 front lower corners of the side plates on a substantially circular arc, a tape guide member comprising a sheet of metal having its side edge portions folded over and into substantial parallelism with the body portions immediately beneath said folded portions but 105 spaced therefrom to establish a pair of thin tape edge guide grooves, the central portion of the guide member intermediate between said folded over portions being longitudinally slotted, the end portions of said slot terminating short of the ends of the guide member to establish cross pieces having projecting ears which are adapted to overlie and be 110 secured to the upper edges of the side plates, 115 said guide member being curved to conform to the curvature of the upper portions of the side plates, a tape gripping and feeding device slidably mounted upon the tape guide member and having a downwardly projecting operating finger extending through and travelling in the slot of the tape guide member, and a swinging arm between the side plates having at its upper end a cross piece 120 which is slotted to receive said downwardly depending finger whereby when the tape guide member and tape gripping and feeding device are set into place on the upper edge portions of the side plates said operating finger 125 properly engages the swinging arm for 130

operation, and whereby the tape guide member, together with the gripping and feeding device may be removed directly away from the side plates.

5 2. In a machine of the class described the combination of a base member, a pair of parallel vertical side plates projecting upwardly from the base member and having their upper portions of suitable shape, a tape 10 guide member comprising a sheet of metal having its side edge portions folded over and into substantial parallelism with the body portions immediately beneath said folded portions but spaced therefrom to establish a pair of thin tape edge guide grooves, the central portion of the guide member intermediate between said folded over portions being longitudinally slotted, the end portions of said slot terminating short of the 15 ends of the guide member to establish cross pieces having projecting ears which are adapted to overlie and be secured to the upper edges of the side plates, said guide member being suitably shaped to conform to the 20 shape of the upper portions of the side plates, a tape gripping and feeding device slidably mounted upon the tape guide member and having a downwardly projecting operating finger extending through and traveling in the slot of the tape guide member, and a swinging arm between the side plates having 25 at its upper end a cross piece which is suitably slotted to receive said downwardly depending finger whereby when the tape 30 guide member and tape gripping and feeding device are set into place on the upper edge portions of the side plates said operating finger properly engages the swinging arm for operation, and whereby the tape guide member together with the gripping and feeding device may be removed directly away from the side plates.

3. In a machine of the class described the combination of a base member, a pair of 45 parallel vertical side plates projecting upwardly from the base member, the upper portions of said side plates being suitably shaped, a tape guide member adapted to occupy a position adjacent to the upper edge portions 50 of the side plates and intermediate between them and suitably shaped to conform to the shapes of the upper portions of the side plates, said tape guide member being provided with a longitudinally extending slot 55 and with means for attachment of its end portions to the upper edges of the side plates, a tape gripping and feeding device slidably mounted upon the tape guide member and having a downwardly projecting operating 60 finger extending through and traveling in the slot of the tape guide member, and a swinging arm between the side plates having at its upper end a cross piece which is slotted to receive said downwardly depending finger 65 whereby when the tape guide member and

tape gripping and feeding device are set into place on the upper edge portions of the side plates said operating finger properly engages the swinging arm for operation, and whereby the tape guide member together with the 70 gripping and feeding device may be removed directly away from the side plates.

4. In a machine of the class described the combination of a base member, a pair of suitably separated supports extending upwardly therefrom and having their upper edges suitably formed, a tape guide member adjacent to and intermediate between said supports and shaped to conform thereto, means in conjunction with said tape guide member for attachment to said supports, the tape guide member being longitudinally slotted, a tape gripping and feeding device slidably mounted upon the tape guide member and having a downwardly projecting operating 80 finger extending through and traveling in the slot of the tape guide member, and a longitudinally movable operating device intermediate between the supports and beneath the tape guide member and having a slotted opening adapted to receive the downwardly projecting finger aforesaid, whereby when the tape guide member and tape gripping and feeding device are set into place on the supports aforesaid said operating finger properly engages the longitudinally movable member, and whereby the tape guide member together with the gripping and feeding device may be removed directly away from the supports.

5. In a machine of the class described the combination with a longitudinally extending tape guide member having a central longitudinal slot together with longitudinally extending tape guide grooves, at the side thereof, of a tape gripping and feeding device 105 slidably mounted upon said tape guide member and including a sheet metal cross piece located above and extending across the tape guide member and having its end portions 110 folded re-entrantly beneath the sides of the tape guide member to retain the gripping and feeding device thereon, said re-entrant portions extending downwardly in the form of separated ears, a bell crank jaw member intermediate between said ears and having its angle pivotally supported on a cross pin extending through said ears, said bell crank jaw member comprising a pair of separated plates of similar shape, a rubber plug located 115 and supported between the arms of the bell crank arm plates and projecting above them to directly engage the surface of the paper tape, there being a downwardly projecting semi-perforation in the gripping and feeding 120 device adapted to co-operate with said rubber plug for gripping purposes, and means for engaging the downwardly projecting arm of the bell crank member to shift the same longitudinally.

6. In a machine of the class described the combination with a longitudinally extending tape guide member having a central longitudinal slot together with longitudinally extending tape guide grooves at the sides thereof, of a tape gripping and feeding device slidably mounted upon said tape guide member and including a sheet metal cross piece located above and extending across the tape guide member and having its end portions folded re-entrantly beneath the sides of the tape guide member to retain the gripping and feeding device thereon, said re-entrant portions extending downwardly to establish a pivot support, a bell crank jaw member having its angle pivoted to said support, a rubber plug secured to the arm of said bell crank jaw member and projecting above the same to engage the surface of the paper tape, a downwardly projecting element on the gripping and feeding device extending into the slot of the tape guide member and adapted to cooperate with the rubber plug for gripping purposes, and means for engaging the downwardly projecting arm of the bell crank jaw member to shift the same longitudinally.

7. In a machine of the class described the combination of a base member, a pair of parallel vertical side plates projecting upwardly therefrom, the upper portions of said side plates curving downwardly from the upper rear corners towards the front lower corners of the side plates on a substantially circular arc, a tape guide member mounted adjacent to said upper edges and conforming generally to the curvature thereof, said tape guiding member being suitably slotted for accommodation of the tape being delivered therethrough, means for advancing the tape longitudinally of the tape guide member, a suitable pocket for a roll of tape resting upon the base member between the side plates, said tape passing upwardly and over the rear edge of the tape guide member, and said rear edge of the tape guide member being provided with a downwardly depending guide finger which is dished with its concave surface facing towards the tape, said dished portion extending up to the point where the tape passes over the rear edge of the guide member and commences longitudinal travel thereof.

8. In a machine of the class described, the

combination of a base member, a pair of parallel vertical side plates projecting upwardly therefrom, a suitable tape guide member adjacent to said upper edges and having a longitudinally extending tape guide groove in which the tape travels, a suitable pocket for a roll of tape above the base member and between the side plates, the tape passing upwardly therefrom and over the rear edge of the tape guide member and into the groove of the tape guide member to commence longitudinal travel therethrough, the rear edge portion of the tape guide member at said point being curved with its concavity facing the tape surface.

9. In a machine of the class described, the combination of a base member, a pair of parallel vertical side plates projecting upwardly therefrom, suitable tape guiding and advancing means in conjunction with the upper portions of the side plates, and a suitable pocket for a roll of tape above the base member and between the side plates, said pocket being dished with its concave surface facing upwardly and with its front edge of higher elevation than its rear edge to thereby naturally resist the tendency of its roll of tape to ride over said front edge.

10. In a machine of the class described the combination with a suitable casing including a pair of separated vertical side plates, of a tape guiding and feeding unit in conjunction therewith and comprising a sheet of metal having its side edges folded over and into substantial parallelism with the body portions immediately beneath said folded portions but spaced therefrom to establish a pair of thin tape edge guide grooves, the central portion of the guide member intermediate between said folded over portions being longitudinally slotted, the end portions of the said slot terminating short of the ends of the guide member to establish cross pieces having projecting ears which are adapted to overlie and be secured to the upper edges of the side plates, and a tape gripping and feeding device slidably mounted upon the tape guide member and having a downwardly projecting operating finger extending through and traveling in the slot of the tape guide member.

RALPH R. SHAY.
